UNITED STATES PATENT OFFICE.

ROBERT W. McGARVEY, OF PHILADELPHIA, PENNSYLVANIA.

SAFETY RAZOR.

Application filed May 20, 1922. Serial No. 562,487.

To all whom it may concern:

Be it known that I, ROBERT W. McGARVEY, a citizen of the United States, residing at Philadelphia, county of Philadelphia, and 5 State of Pennsylvania, have invented certain new and useful Improvements in Safety Razors, of which the following is a specification.

The present invention relates to safety 10 razors.

The purpose of the invention is to provide a strong and serviceable safety razor which is efficient in use and readily adjustable for close or coarse shaving, and at the 15 same time has few parts, the parts being of simple design so that the entire razor may be fabricated at small expense. The razor is designed so that the blade may be stropped either manually upon the ordinary razor strop, or in a stropping device such as that described and illustrated in 20 my copending application Serial No. 562,488, filed May 20, 1922. A feature of the invention resides in the novel blade holding 25 means, a holder being provided for firmly holding the blades but in such manner that they may be easily and conveniently detached therefrom for the purpose of replacement.

30 In the accompanying drawings two forms of the razor are illustrated and in the following description the construction of these modifications is explained in detail, but it will be understood that the scope of the invention is not limited to the two forms illustrated and described but contemplates that changes in design and arrangement of the component parts of the invention may be made when found convenient.

40 In the drawings:

Fig. 1 is a longitudinal sectional view through one form of razor;

Fig. 2 is an elevation of the same as viewed from the back;

45 Fig. 3 is a side elevation of this razor shown in position to be stopped;

Fig. 4 is an enlarged section through the head of the razor;

50 Figs. 5 and 6 are plan views of the razor blade adjusting cam in two different positions;

Fig. 7 is a plan view of the blade holder with blade attached;

55 Fig. 8 is a section on line 8—8 of Fig. 7;

Fig. 9 is a side elevation of a modified form of razor;

Fig. 10 is a rear elevation of the same;

Fig. 11 is an enlarged sectional view through the head of the modified razor; and

Fig. 12 is a plan view of the blade holding plate.

In the form of the invention illustrated in Figs. 1 to 8 inclusive the handle is formed from a hollow tube 10 closed at one 65 end by a plug 11 and having outwardly and oppositely curved arms 12 at its other end. A circular cross bar 13 is secured by rivets 14 to arms 12 and this bar is recessed to receive the inner edge of the guard plate 70 15, or if desired the bar may be formed in two portions secured together and clamping the guard plate between them.

The blade holder comprises a plate 16 having a reduced portion 17 which is curved 75 and which extends around bar 13 and fits closely against its outer surface. The blade holder may swing about the bar from the position in which it is illustrated in Fig. 4, and in full lines in Fig. 3, to the position 80 in which it is illustrated in dotted lines in Figs. 3 and 4. Movement of the blade holder in one direction is limited by the guard against which it directly abuts, and movement in the opposite direction is limited by 85 abutment of the shoulders 18 against the adjacent edges of the arms 12 of the handle. In stropping the razor manually on a strop such as indicated at S in Fig. 3, the blade oscillates between these two limiting stops, 90 and the operator is enabled to sharpen the blade which is secured to the plate 16 by moving it along a strop in the usual manner, effecting the reversal of the blade holding plate by means of the fore finger which is 95 pressed against the portion 17 of the blade holder to exert a slight tangential force so that the rotation of this sleeve-like portion and hence of the blade holder around the axle or bar 13 is effected at the termination 100 of each stroke in the stopping operation, the blade being lifted from the strop when being reversed.

At the ends of the blade holding plate 16 are retaining flanges 19 which extend around and over the ends of the razor blade 20 and prevent transverse movement thereof. Plate 16 is provided centrally with a tongue 21 which is struck downwardly from the body of the plate and constitutes a catch which 110 is adapted to enter an opening 22 in the center of the blade and near its rear or

blunt edge. In inserting a blade into the holder its rear corners are inserted under the retaining flanges 19 and the blade pushed rearwardly or toward the bar 17, its center 5 springing slightly away from the plate as it contacts with the projecting catch 21. When the opening 22 reaches and passes over this catch, the blade snaps flat against the plate and is retained by the catch against 10 movement away from the bar 13. Its removal may be effected quickly and easily by springing upwardly its center portion with the fingers so that the catch 21 disengages the opening 22 and in then drawing 15 the blade forwardly so that its edges disengage the retaining flanges 19.

As the blade holder is mounted upon the bar 13 for free rotation thereon it is necessary to provide means for locking the same 20 in shaving position. Sleeve 17 of the blade holder is provided with an opening 25 which is adapted to be engaged by the substantially conical end 26 of a spindle 27 secured to the upper end of a plunger 28 which is slidably contained within the handle 10 and normally pressed toward the bar 13 by means of a spring 29. A projection 30 extending laterally from the plunger 28 constitutes a handle by means of which the user may 25 retract the plunger by means of his thumb or finger so that the spindle 27 disengages the opening 25 to allow rotation of the blade holder, and the handle 10 is provided with a notch 31 to receive member 30 so that the 30 plunger may be locked in retracted position if desired by turning the plunger so that the member 30 enters the notch 31.

It will be seen that the end 26 of spindle 27 tapers upwardly or is substantially conical 35 but that the apex of the tapered portion is to one side of the axis of the spindle 27. This tapered end 26 therefore constitutes a cam and it will be seen that by rotating the plunger 28 in the direction of the arrows 40 (Figs. 5 and 6) from the full line position in Fig. 5 to the full line position in Fig. 6, the apex of the cam will be moved from the right toward the left, and from this it follows that the sleeve 17 will be rotated to a slight extent thereby causing the blade holder 16 to be moved slightly relatively to the guard 15. This movement though slight, 45 enables the user to regulate as he desires the degree of closeness of shaving.

In my copending application before mentioned, is described a stropping device by means of which the razor herein disclosed may be efficiently stropped by rotation of a handle or crank. For properly positioning 50 the razor blade for stropping and for holding the same in such position I have provided in the sleeve 17 a second aperture 32 which may also be engaged by spindle 27 so that the blade is held in the position in 55 which it is illustrated in Fig. 4, pressure of

the spring 29 preventing disengagement of the spindle from the aperture 32. The parallel slots 33 in the plug 11 are adapted to cooperate with a holding device in the stropping mechanism to prevent rotation of the 60 handle during the stropping operation.

In the form of razor illustrated in Figs. 9, 10, 11 and 12 the handle 10' is preferably solid and the guard plate 15' has a portion which enters a slot in the end of the handle 70 and is secured therein by rivets 14'. The cross bar 13' is formed in two portions riveted to the parallel upwardly extending arms 15' of the guard plate. The blade holder is formed exactly as in the first described 80 form of the invention with the exception that the circular holes or apertures in the sleeve 17 of the first modification are replaced by slots 25' and 32' extending longitudinally of the sleeve 17'. A flat member or lever 35 is pivoted at 36 and the upper end of this lever is adapted to enter either of the slots 25' or 32'. When extending within slot 32' the blade holder is locked with the blade in position to be stropped in 90 a stropping machine, this position being shown in dotted lines in Fig. 9. It will be seen from Figs. 10 and 12 that the slot 25' extends diagonally to an element of the cylindrical sleeve 17', and in reality this 95 slot constitutes a cam slot adapted to cooperate with lever 35 in effecting the adjustment of the blade holding plate relatively to the guard to obtain different degrees of closeness in shaving. It will be seen that 100 inasmuch as the lever 35 swings about a fixed axis and in a fixed plane, that movement of this lever longitudinally in slot 25' will cause rotation of the sleeve and hence 105 movement of the cutting blade relatively to the guard. Two possible positions are shown in full and dotted lines in Fig. 11. Parallel transverse slots 33' are shown at the opposite end of the handle for cooperation with the holding device in the stropping mechanism with which the razor is particularly 110 adapted to be used.

It will be understood that the invention is not limited to the two forms of razors illustrated and described but that its principles may be embodied in still further modifications.

Having thus described my invention, what I claim as new and desire to secure by Letters Patent is:

1. A safety razor comprising in combination, a handle, a fixed guard, a swinging blade holder, and a member rotatable about a fixed axis and adapted for linear movement, for adjusting the angular relationship of the guard and blade holder in regulating closeness of shaving and for locking the blade holder in any one of a plurality of positions relatively to the handle and guard.

2. A safety razor comprising in combination, a handle, a guard, a swinging blade holder, and a cam member mounted on the handle and having a cam surface engaging the blade holder and rotatable about the axis of the handle for adjusting the angular relationship of the guard and blade holder in regulating closeness of shaving.
3. A safety razor comprising in combination, a handle, a guard rigid therewith, a swinging blade holder, and a member moveably mounted on the handle and engaging the blade holder beneath the guard for locking the same in shaving position or stropping position, said blade holder being freely oscillatable when disengaged by said locking member.
4. A safety razor comprising in combination, a handle, a guard fixed with respect to the handle, a blade holder mounted to swing about an axis fixed with respect to the handle, and a member moveably mounted on the handle and engaging the blade holder for locking the same in shaving position or stropping position, and means normally pressing said member into engagement with the blade holder.
5. A safety razor comprising in combination a handle, a guard fixed with respect to the handle, a swinging blade holder having a plurality of apertures therein, and movable means mounted on the handle and adapted to enter any one of said apertures to lock the blade holder in any one of a plurality of positions.
6. A safety razor comprising in combination a handle, a guard fixed with respect to the handle, a swinging blade holder having a plurality of apertures therein any one of which may be brought into alignment with the axis of the handle, and a member moveable axially of the handle and adapted to enter any one of said apertures to lock the blade holder against movement.
7. A safety razor comprising in combination, a handle, a guard fixed in respect thereto, a swinging blade holder, and means cooperating with the holder for locking the same in shaving position or stropping position, which means may be adjusted to permit free swinging movement of said blade holder.
8. A safety razor comprising in combination a handle having a cross piece, a blade holder having a sleeve portion extending around the crosspiece and provided with a plurality of apertures, the blade holder being adapted to swing about the cross piece, and a member supported on the handle and movable axially thereof to extend within one of said apertures to lock the blade holder against rotation.
9. A safety razor comprising in combination a handle having a cross piece, a blade holder having a sleeve portion extending around the cross piece and provided with a circular hole, the blade holder being adapted to swing about the cross piece, and a member having a conical end movably supported on the handle and having a cone extending within said hole for adjusting the angular position of the blade holder relatively to the handle.
10. A safety razor comprising in combination a handle having a cross piece, a blade holder having a sleeve portion extending around the cross piece and provided with a circular aperture, the blade holder being adapted to swing about the cross piece, and a cam member supported on the handle and adapted to extend into said aperture and to engage its edges, said cam member being rotatable about the axis of the handle for adjusting the angular position of the blade holder relatively to the handle.
11. A safety razor having a handle, diverging arms thereon, a guard, a blade holder pivoted to the arm, and an abutment on the blade holder intermediate the cutting and rear edges of the blade adapted to engage said arms to limit the swinging movement of the blade away from the guard in stropping.
12. A safety razor, comprising in combination, a handle, a fixed guard, a blade holder mounted to swing in relation to said guard, a blade in said holder, and means associated with said handle to positively adjust the angular relation of said guard and blade toward and from each other.

In testimony whereof I hereunto affix my signature.

ROBERT W. McGARVEY.
